(57) **CLAIM**

The ornamental design for plant-based meat replacement product as shown and described.

DESCRIPTION

Figure 1.1 is a top, left side and back perspective view of a plant-based meat replacement product;

Figure 1.2 is a front perspective view thereof;

Figure 1.3 is a right side elevation view thereof;

Figure 1.4 is a top plan view thereof;

Figure 1.5 is a top and right side perspective view thereof;

Figure 1.6 is a cross sectional view thereof;

Figure 1.7 is another cross sectional view thereof;

Figure 2.1 is a top, left side and back perspective view of a second embodiment of a plant-based meat replacement product;

Figure 2.2 is a front elevation view thereof;

Figure 2.3 is a right side elevation view thereof;

Figure 2.4 is a top plan view thereof;

Figure 2.5 is a bottom plan view thereof;

Figure 2.6 is a left side elevation view thereof;

Figure 2.7 is a back elevation view thereof;

Figure 3.1 is a top, left side and back perspective view of a third embodiment of a plant-based meat replacement product;

Figure 3.2 is a front elevation view thereof;

Figure 3.3 is a right side elevation view thereof;

Figure 3.4 is a top plan view thereof;

Figure 3.5 is a bottom plan view thereof;

Figure 3.6 is a left side elevation view thereof;

Figure 3.7 is a back elevation view thereof.

The evenly-spaced broken lines shown in Figures 3.1-3.4 and 3.6-3.7 illustrate portions of the plant-based meat replacement product that form no part of the claimed design. The dash-dot-dash broken lines in Figures 3.1-3.3 and 3.6-3.7 illustrate the boundary of the claimed design which forms no part thereof.
